COMPRESSOR

French E. Dennison, York, Pa., assignor to York
Ice Machinery Corporation, York, Pa., a cor-
poration of Delaware

Application March 19, 1934, Serial No. 716,383

10 Claims. (Cl. 230—190)

This invention relates to compressors, and particularly to means for unloading the compressor when at rest, without involving material slip or leakage while the compressor is in operation.

5 The principal advantage of the unloading means disclosed, is the fact that it involves no moving parts, and thus accomplishes the desired result in the simplest possible manner.

The invention is intended chiefly for use in 10 small refrigerating units of the compressor, condenser, evaporator circuit type, but is available for use in other situations.

If the compressor stops, with the piston on the compression stroke, or if there is slight leakage 15 from the discharge of the compressor through the discharge valve to the cylinder, the starting load on the motor which drives the compressor will be considerable, and to meet this condition it has heretofore been the practice to use a motor with 20 a high starting torque which entails the use of an unnecessarily large and heavy motor, or else to provide some automatic unloading means which opens an unloading port when the compressor comes to rest. The latter expedient involves the use of rather sensitive and expensive 25 mechanism and does not protect the motor from overload in the event that the unloading mechanism fails to function. Most known unloading mechanisms are subject to occasional failures to 30 function.

The present invention involves the use of a bleed port which becomes effective to unload the compressor when the compressor stops and which is sealed against leakage when the compressor is 35 in motion. Generally stated, the invention contemplates the use of one or more radial ports extending through the piston above the uppermost piston ring and below the top of the piston. These ports are preferably located in the plane 40 of the axis of the wrist pin so as not to be materially affected by wear of the piston or cylinder.

While it is impossible to state positively the principle of operation of these ports, careful tests 45 of compressors embodying the invention, show that the leakage through the ports when the compressor is in operation, is negligible, but becomes sufficient to relieve the pressure in the working space of the compressor whenever the compressor is at rest.

50 A possible explanation of this action is the fact that when the compressor is in operation, an oil film is maintained between the piston and the cylinder walls, and enough of this oil film is delivered to the unloading ports to preclude substantial flow through the ports. On the other

hand, when the compressor is at rest, this film is not maintained, so that the ports are blown free of oil and serve to unload the compressor at a rate sufficiently rapid to ensure unloading by the time the compressor is restarted.

Other factors which assist in precluding back flow through the unloading port are the rather high piston speed and the arrangement of the port at a right angle to the path of reciprocation of the piston, and to the cylinder wall. There is what may be described as a labyrinth effect, and this is particularly pronounced at high piston speeds.

The preferred embodiment of the invention as applied to an air-cooled compressor of a type extensively used in refrigerating units, will now be described in connection with the accompanying drawing, in which the single figure is a vertical axial section of one cylinder of a multi-cylinder compressor with the invention applied.

In the drawing, 5 represents the cylinder wall provided with cooling fins 6. The upper end of the cylinder is closed by a head 7 having discharge ports 8 arranged in a circular series concentric with the cylinder. Clamped to the center of the head 7 by means of a bolt 9, nut 11 and lock nut 12, is a flexible disk valve 13, which coacts with the annular seat ribs 14 and 15 between which the ports 8 are located. The disk 13 is ported, as indicated at 16, and controls flow to the discharge passage 17 which is enclosed by a housing 18. The housing 18 is provided with cooling fins 19 and is held to the cylinder casting by machine screws 21 which pass through a flange on the housing 18 and through the head 7 into threaded engagement with a flange at the upper end of the cylinder 5.

The intake port of the compressor is indicated at 22 and extends through the wall of the cylinder 5. It is so located as to communicate with the middle or web portion of a trunk piston comprising an upper head 23 and a lower head 24 connected by a web structure 25. The upper head 23 is provided with metallic piston rings 26, of which three are illustrated. The lower head 24 is provided with oil rings 27 and 28, the ring 28 being of the slotted oil draining type. The head 24 is immediately below the piston pin or wrist pin 29 to which the connecting rod 31 is connected. The rod 31 is connected to the usual crank (not shown) and forms a part of the means for reciprocating the piston.

The intake valve is mounted on the upper face of the head 23 and comprises a flexible valve disk 32, similar to the disk 13 and coact-

ing with ribs 33 and 34 similar to the ribs 14 and 15. The suction ports 35 are located between the ribs 33 and 34. The disk 32 is held to the head 23 by means of the screw 36.

5 The parts so far described conform generally to known construction and no novelty is claimed for these parts in the present application. They are illustrated as typical of compressor construction and are chosen for illustration merely 10 10 because the construction is standard for one type of compressor manufactured by applicant's assignee.

A short distance below the upper margin of 15 the head 23 and a short distance above the upper piston ring 26 are unloading ports 37 forming the subject matter of the present invention. As illustrated two such unloading ports are used extending laterally through the head 23 with their axes in a plane common to the axis of the wrist 20 pin 29 and the axis of cylinder 5. This location is chosen because at such points the cylinder and piston are subject to the minimum wear.

While the location of the ports in the plane defined is preferred, the invention is not limited 25 strictly in this respect. For example, if more than two ports are used they can not be located strictly in this plane, but it is considered better practice to locate them as close to this plane as possible.

30 Generally stated, it is desirable that the ports 37 be of small diameter because the closing effect of oil is more pronounced with small ports than with large ones. Consequently, in some cases where considerable unloading capacity is 35 necessary, it may prove desirable to use more than the two ports illustrated. Furthermore, the size of these ports is somewhat exaggerated in the drawing for the purpose of making them clearly visible.

40 Practical tests have shown that when the piston head 23 is reciprocating, that is, when the compressor is in operation, the leakage through the ports 37 is so small as to be negligible, but when the piston comes to rest, and particularly 45 if it be at rest under conditions in which there is a substantial pressure in the working space between the top of the piston head 23 and head 7, the ports will function to dissipate that pressure to the suction side of the head 23 and thus 50 unload the compressor.

From the standpoints of maintenance, manufacture and certainty of operation, the invention has outstanding advantages. Since there are no moving parts, there is nothing to maintain and no possibility of a failure to function. 55 The application of the invention involves merely the drilling of a few small ports, so that the invention can be inexpensively applied to existing compressors, as well as to new equipment.

60 The ability to use successfully a motor only large enough to carry the running load offered by the compressor, results in a substantial saving in the first cost of the plant.

While it is not necessary that the unloading 65 ports 37 be strictly radial, it is considered desirable that they be so. Further, it is believed that there is some operative coaction between these radial ports and the rings 26, the rings serving to distribute and control the oil film, 70 which is believed to exercise at least a partial sealing action on the ports 37 while the compressor is in operation.

While the suction and discharge valve mecha-

nism has been described in considerable detail, this is merely for the purpose of illustrating one practical embodiment of the invention, and implies no necessary limitation of the use of the invention with any particular valve or type of valve. 5

What is claimed is,—

1. The combination of a compressor of the type comprising a cylinder and a reciprocating piston; and at least one unloading port of restricted size leading from a space at relatively low pressure through the peripheral walls of the piston to the area of contact between piston and cylinder. 10

2. The combination of a compressor of the type comprising a cylinder and a reciprocating piston having packing rings; and at least one unloading port of restricted size leading from a space at relatively low pressure through the peripheral wall of the piston to the area of contact between the cylinder and piston at a point between the working space in the cylinder and the ring nearest thereto. 20

3. The combination of a compressor of the type comprising a cylinder and a reciprocating piston having a wrist pin; and at least one unloading port of restricted size leading from a space at relatively low pressure through the peripheral wall of the piston to the area of contact between piston and cylinder, said port being located substantially in a plane common to 30 the axes of the cylinder and wrist pin. 25

4. The combination of a compressor of the type comprising a cylinder and a reciprocating piston having packing rings and a wrist pin; and at least one unloading port of restricted size 35 leading from a space at relatively low pressure through the peripheral wall of the piston to the area of contact between the cylinder and piston, at a point between the working space in the cylinder and the ring nearest thereto, said port 40 being located substantially in a plane common to the axes of said cylinder and wrist pin. 45

5. In a compressor, the combination of a cylinder; a piston dividing said cylinder into a suction space and a compression space; and a restricted unloading port leading from said suction space through the periphery of said piston to the area of contact of said piston and cylinder. 55

6. In a compressor, the combination of a cylinder; a piston dividing said cylinder into a suction space and a compression space; piston rings sealing said piston in said cylinder; and a restricted unloading port leading from said suction space through the periphery of the piston to the area of contact of the piston and cylinder between said rings and said compression space. 50 55

7. The combination defined in claim 1, in which said space at relatively low pressure is in communication with the suction connection of the compressor. 60

8. The combination defined in claim 2, in which said space at relatively low pressure is in communication with the suction connection of the compressor. 65

9. The combination defined in claim 3, in which said space at relatively low pressure is in communication with the suction connection of the compressor. 70

10. The combination defined in claim 4, in which said space at relatively low pressure is in communication with the suction connection of the compressor. 75
